UNITED STATES PATENT OFFICE.

OCTAWE C. NATALIS, OF CHARLESTON, WEST VIRGINIA.

STRENGTH-REGULATOR FOR TANK-DRAWN MACHINE WINDOW-GLASS.

1,251,561.

Specification of Letters Patent.

Patented Jan. 1, 1918.

Application filed February 28, 1917. Serial No. 151,474.

To all whom it may concern:

Be it known that I, OCTAWE C. NATALIS, residing at Charleston, in the county of Kanawha and State of West Virginia, have 5 invented certain new and useful Improvements in Strength-Regulators for Tank-Drawn Machine Window-Glass, of which the following is a specification.

In the art of manufacturing window glass, 10 one of the methods employed is to draw the glass from the tank in the form of a cylinder which is afterward slit and flattened into sheets. In drawing glass cylinders, the temperature of the drawn part is subjected to 15 variation, due to the air currents, and to the heat from the cooling chamber which is located principally on one side of the work. This causes the glass to become thinner in some places than in others and consequently 20 weakens the structure at the different places. It is therefore one of the objects of my invention to provide a means for overcoming this objectionable feature by making it possible to apply either a cooling blast or a heating 25 blast to the glass as it is drawn from the tank, provision being made whereby the temperature of the blast may be varied at different places or zones throughout the annulus of the cylinder according to the particu- 30 lar condition existing at the time at that place, to thereby produce a product of uniform thickness and strength. Provision is further made whereby not only the adjustment may be individually effected to regulate 35 the proportionate effect of the blast at the different places, but the entire series of parts may be regulated in unison, if desired.

More specifically, my invention provides 40 a ring-pipe which encircles the drawn glass cylinder at a place close to the tank and is divided into a series of sections or pockets having ports directed toward the cylinder, each pocket being supplied with air or gas 45 from a tank by an individual duct in which a control valve is located. The several valves have gear-connected stem-wheels whereby they may all be turned in unison by a master gear wheel to open or close all 50 valves together. The several valves also have individual provisions whereby anyone or more of them may be separately adjusted to regulate the flow of fluid passing through the particular duct or ducts to the particular 55 section or sections of the ring-pipe, without disturbing the adjustment of the remainder.

More specifically, the invention includes those novel details of construction, combination and arrangement of parts, all of which will be first fully described, then be pointed out specifically in the appended claims, and illustrated in the accompanying drawing, in which:—

Figure 1 is a top plan view illustrating the invention in use. 65

Fig. 2 is an enlarged detail section showing one method of constructing the ring-pipe and connecting the ducts to the same.

Fig. 3 is a side elevation of one of the valves showing the means employed for individual and collective adjustment. 70

Fig. 4 is a detail section on the line 4—4 of Fig. 3.

In the drawing, in which like letters and numerals of reference indicate like parts in 75 all of the figures, 8 represents ducts which supply air or gas from the tank 18 to the separate compartments 13^a of the ring-pipe 13, suitable shutoff or control valves 19 being employed in each duct and for convenience 80 these valves are preferably located adjacent to the tank.

The ring-pipe 13 is composed of sections which are coupled together as at 15, end to end, by plugs which are threaded or welded, 85 or otherwise rigidly secured to the pipe ends and serve as cutoffs or dams in the ring-pipe to divide the ring-pipe into a series of chambers or sections 13^a. 14 designates unions which connect the ring-pipe sections 90 with the respective ducts, the connection between the ducts and the ring-pipe being made in any desired manner.

The ring-pipe 13 is provided with small perforations or ports 16 on the side adjacent 95 to the cylinder 17 that is being drawn.

The construction of the valves 19, *per se*, may be of any approved type, but the stems 20—20 are provided with feather grooves 21 in the direction of their length to receive the feather or lug 23 of the respective gear wheel 22 by which the valve stem is turned to open or close the valve 19. The gear wheel 22 is held in a definite normal plane against the washer 24 and jam nut 25 by a spring 29 interposed between the wheel 21 and the gland cap 30 of the valve so that all of the wheels 22 under normal condition are held in the same plane and the several valves are so located with relation to adjacent valves that 100 the gear wheels 22 of all valves mesh in train (see Fig. 1). 26 is a master gear which 105

meshes with the adjacent valve gear and may be provided with any means by which it can be turned to operate the gear wheel train as, for instance, the crank 27.

5 In practice, the ring 13 is preferably located closely to the tank from which the glass cylinder is drawn and when the tank 18 is filled with compressed air it serves the purpose of supplying a cooling blast to 10 the cylinder 17 to effect a cooling action on the drawn glass. It is found, in practice, that the temperature of the glass is not uniform throughout the annulus of the cylinder and hence it is necessary to regulate 15 the blast to different degrees of action at different places. The operator can accomplish this act by depressing the gear wheel 22 of the particular control valve and opening or closing that valve manually, 20 while the gear wheel is depressed until the proper blast action is obtained for the particular place; after which the valve gear 22 that has been depressed is permitted to come back into place and remesh with the 25 adjacent valve gears.

After the individual valves have been set to deliver the proper blast to the particular points desired the intensity of the blast, as a system or a whole, can be increased or diminished uniformly by turning the master gear 26 and operating all valves simultaneously. It should be understood that alternate valves are rights and lefts so that when the master gear 26 is turned in one direction 30 all valves will be opened and when it is turned in the opposite direction the valves will be closed.

It will be seen that by the use of my invention a very effective, inexpensive and 40 readily controlled mechanism is provided for the purposes and the convenient valve control arrangement enables quick adjustments to be made to meet conditions as they arise and having once set the valves to enable a 45 proper distribution of air to the blast, so long as the conditions of temperature at the machine remain the same, all of the valves can be opened or closed together for increasing or diminishing the blast in the same proportion 50 at all places.

Instead of using air for a cooling blast the tank 18 may be employed to contain gas which can be ignited at the aperture 16 and used as a heating blast, in which event, of 55 course, the opposite action takes place on the drawn glass cylinder and it is kept at a uniform elevated temperature rather than uniformly cool.

I desire it understood that changes in the 60 details of construction and arrangement of parts may be made without departing from the spirit of the invention or the scope of the appended claims, and from the foregoing description taken in connection with 65 the accompanying drawing, it is thought the

complete construction, operation and advantages of my invention will be readily understood by those skilled in the art.

What I claim is:—

1. In an apparatus of the class described, 70 a cylinder encircling tubular body having separate pockets that are provided with discharge ports directed toward the cylinder, a tank, a set of ducts connecting the respective pockets with the tank, individually operable control valves for each pocket duct, and a common operating mechanism for simultaneously opening or closing said valves.

2. In an apparatus of the class described, 80 a cylinder encircling tubular body having separate pockets that are provided with discharge ports directed toward the cylinder, a tank, a set of ducts connecting the respective pockets with the tank, individually operable control valves for each pocket duct, each valve having a stem, means coöperative with all of the stems for simultaneously turning the same to open or close the valves 85 as a set.

3. In an apparatus of the class described, a cylinder encircling tubular body having separate pockets that are provided with discharge ports directed toward the cylinder, a tank, a set of ducts connecting the respective pockets with the tank, individually operable control valves for each pocket duct, each valve having a stem, means coöperative with all of the stems for simultaneously turning the same to open or close 90 the valves as a set, each valve having provision for individual adjustment independently of the others.

4. In an apparatus of the class described, 95 a cylinder encircling tubular body having separate pockets that are provided with discharge ports directed toward the cylinder, a tank, a set of ducts connecting the respective pockets with the tank, individual control valves for each pocket duct, each valve 100 having a stem, a gear wheel on each stem slidably keyed to the respective stem, means for holding the said gear wheels in mesh, and means for simultaneously turning said 105 valve stem gear wheels.

5. In an apparatus of the class described, 110 a cylinder encircling tubular body having separate pockets that are provided with discharge ports directed toward the cylinder, a tank, a set of ducts connecting the respective pockets with the tank, individual control valves for each pocket duct, each valve having a stem, a gear wheel on each stem 115 slidably keyed to the respective stem, means for holding the said gear wheels in mesh 120 whereby all of said valves may be operated together.

6. In an apparatus of the class described, 125 a cylinder encircling tubular body having separate pockets that are provided with dis- 130

charge ports directed toward the cylinder, a tank, a set of ducts connecting the respective pockets with the tank, individual control valves for each pocket duct, each valve having a stem, a gear wheel on each stem and slidably keyed to the respective stem, a spring on each stem for holding the respective gear wheels in the same place and in a meshing train whereby all of the valves may 10 be turned in unison.

7. In an apparatus of the class described, a cylinder encircling body having separate pockets that are provided with discharge

ports directed toward the cylinder, a tank, a set of ducts connecting the respective 15 pockets with the tank, individual control valves for each pocket duct, each valve having a stem, a gear wheel on each stem slidably keyed to the respective stem, a spring on each stem for holding the respective gear 20 wheels in the same plane and in a meshing train, and a master gear meshing with one of said gear wheels for turning the entire gear train.

OCTAVE C. NATALIS.
